(57) **CLAIM**

The ornamental design for a tree branch antenna concealment anchor as shown and described herein.

DESCRIPTION

FIG. 1 is a perspective view of a first embodiment of a tree branch antenna concealment anchor showing the new design;

FIG. 2 is a top view of the first embodiment of the tree branch antenna concealment anchor;

FIG. 3 is a side view of the first embodiment of the tree branch antenna concealment anchor;

FIG. 4 is an end view of the first embodiment of the tree branch antenna concealment anchor;

FIG. 5 is a perspective view of a second embodiment of a tree branch antenna concealment anchor showing the new design;

FIG. 6 is a top view of the second embodiment of the tree branch antenna concealment anchor;

FIG. 7 is a side view of the second embodiment of the tree branch antenna concealment anchor; and,

FIG. 8 is an end view of the second embodiment of the tree branch antenna concealment anchor.

1 Claim, 4 Drawing Sheets
